UNITED STATES PATENT OFFICE.

JOHN F. KELLY, OF CHICAGO, ILLINOIS.

STARTER FOR HYDROCARBON-ENGINES.

1,072,385.

Specification of Letters Patent. Patented Sept. 2, 1913.

Application filed January 26, 1912. Serial No. 673,680.

To all whom it may concern:

Be it known that I, JOHN F. KELLY, a citizen of the United States of America, and a resident of Chicago, county of Cook, State 5 of Illinois, have invented certain new and useful Improvements in Starters for Hydrocarbon-Engines, of which the following is a specification.

The main objects of this invention are to 10 provide an improved form of starting device for multi-cylinder internal combustion engines adapted to permit the operator to start the engine at will without resorting to cranking; to provide a device of this kind, which 15 is of compact form and adapted to be connected up as a unitary structure for convenient attachment to the engine of a motor driven vehicle; to provide in devices of this class an improved construction whereby 20 the distribution of the starting fluid to the various cylinders of the engine is controlled by cams so arranged relative to each other as to open communication with the cylinders in succession, and in the same order in which 25 such cylinders commence their expansion strokes, and to provide a device of this kind which is capable of starting the engine regardless of whether or not it has stopped on dead center.

30 An illustrative construction embodying this invention is shown in the accompanying drawings in which—

Figure 1 is a side elevation partly in section of a starting device constructed as a unit 35 and adapted for connection with the crank-shaft of a multi-cylinder internal combustion engine for use as a starting device for such engine. Fig. 2 is a top plan of the same, the storage reservoir being omitted for 40 the sake of more clearly illustrating the arrangement of the valves, the line A A indicating the plane on which the section is taken. Fig. 3 is a sectional detail of the valve mechanism, the section being taken at 45 right-angles to the plane of Fig. 1 and being indicated by the line B B of Fig. 1. Fig. 4 is a sectional elevation of a gas engine cylinder and the air pump illustrating diagrammatically their relative arrangement and 50 connection with the engine piston being shown on dead center position.

In the construction shown in the drawings there is provided a pressure reservoir 1 having a blow-off valve 2 which acts as a safety valve and limits the pressure of the charge 55 in the reservoir. An air compressor 3 is connected with the reservoir 1 by means of a pipe 4 having a check valve 5. The cylinder of the compressor 3 is mounted upon a base 6 in which is journaled a shaft 7 having 60 a crank 8 arranged to operate the piston 9 of the compressor through a pitman 10, and having also a series of cams 11. Also mounted on the base 6 is a series of valve casings 12, each having therein a balanced piston 65 valve 13 normally urged by a spring 14 to a closed position, and provided with an operating stem 15 arranged to be actuated by one of the cams 11. A supply pipe or manifold 16 communicates with each of the valve 70 casings 12, and is also connected to the reservoir 1. The connection to the reservoir is controlled by a valve 17 connected by suitable linkage with a treadle 18 conveniently located with respect to the operator's seat. 75 A spring 19 normally urges the valve 17 to a closed position, and the linkage is such that pressure on the treadle 18 opens the valve. The valve casings and cams 11 correspond in number with the cylinders of the engine (not 80 shown), to which the device is connected, and each of the valve casings 12 has a pipe 20 leading from it to the respective cylinder of the engine. These pipes serve as inlet 85 pipes for the engine during starting. Each of the pipes 20 has a check valve 21 to prevent the backward flow of gas from the engine to the valves 13. The cam-shaft 7 is connected to the engine by mechanism so geared and timed as to cause the valves 13 to 90 open in harmony with the movements of the engine pistons; that is to say, in a four-cycle engine the shaft 7 would rotate at half the speed of the crank-shaft of the engine, and would be so connected that the opening of 95 the valves 13 would correspond in order with the commencement of the expansion strokes of the respective engine pistons. Each cam 11 may be of such form as to keep the valve 13 open throughout the greater part of the 100 length of the expansion stroke of the piston of the respective engine cylinder. If the

crank arrangement of the engine has a dead center, the starter is provided with a by-pass connection 22 around the check valve 5 and the gearing between the crank-shaft of the engine and the cam-shaft 7 is so connected that the crank 8 and the engine crank shaft cannot be simultaneously on dead center. A treadle 24 acting through linkage 25 opens the valve 22 and allows the reservoir pressure to shift the piston 9 enough to throw the engine off dead center if it has stopped in that position.

The operation of the device shown is as follows: In the particular construction shown it is intended that the compressor will operate whenever the engine runs, and as the running period is long as compared with the intervals during which the starting mechanism is required, the compressor cylinder 20 may be of small capacity as compared with that of the individual engine cylinders. The capacity of the reservoir 1 should, however, be sufficiently large to provide a charge of ample volume to start the engine whenever 25 called upon to do so. In starting, one cylinder after another is charged with air until one or more of the pistons makes its normal suction and compression strokes as in the normal running of the engine, whereupon 30 ignition will take place and will continue to run under its own power. During the normal running of the engine the compressor 3 at each stroke forces a small quantity of air into the reservoir 1, and as soon as the pressure 35 in said reservoir has reached the predetermined maximum for which the blow-off valve is set, this blow-off valve will operate to prevent the pressure from exceeding said maximum, but will also prevent it from 40 falling below. When the engine is at rest the operator may start it by pressing his foot upon the treadle 18. This opens the valve 17 and admits air to the manifold 16. The valves 13 then distribute the compressed air 45 to the cylinders, as described, to start the engine. If the engine is on dead center, and does not start on pressing the treadle 18, it may be thrown off of dead center by pressing the treadle 24. The pressing of the treadle 50 24 opens the valve 23 and permits the compressed air to enter the pump chamber 3 and force the piston 9 downwardly, which causes the engine piston to be moved off its dead center position. As the engine piston 55 is shifted from its dead center position, the cam 11 opens the respective valve 12, so as to admit air from the reservoir into the cylinder, and thereby continue the initial movement of the engine piston.

60 The maximum pressure for which the blow-off valve 2 is set, should be a pressure somewhat greater than that to which the fuel and air are compressed in the engine cylinders previous to ignition, so that the inflow 65 of air for starting the engine will be capable

of overcoming the pressure of the residuary charge which may happen to be present in a cylinder which stopped during the compression stroke of its piston.

Since the valves 13 are open only during expansion strokes of the respective engine pistons, the pressure in the engine cylinders during normal operation of the engine will during the combustion of the charges in the cylinders exceed the pressure of the reservoir 1, and, therefore, even though the valves 70 13 open and the valve 17 may be held open, no air will be admitted to the engine cylinders from the reservoir since the check valves 21 would be held closed by the pressure of 75 the gas in the engine cylinders. For this reason the starting of the engine requires no action or attention on the part of the operator further than to push down the treadle 18 and to hold it depressed until the engine is 80 running at normal speed.

Although but one specific embodiment of 85 this invention is herein shown and described, it will be understood that numerous details of the construction shown may be altered or omitted without departing from the spirit of 90 this invention as defined by the following claims.

I claim:—

1. A starting device for internal combustion engines, comprising a storage reservoir, mechanism adapted to distribute air from said reservoir to said engine for starting the same, an air cylinder connected to said reservoir, a piston mounted in said cylinder and connected to the shaft of said engine, means for delivering air from said reservoir to said cylinder whereby said piston may be operated for shifting the engine off dead center, and means adapted to control the operation 95 of said mechanism so as to cause the introduction of air into the cylinder of said engine as the engine is shifted off dead center.

2. A starting device for multi-cylinder internal combustion engines comprising a storage reservoir, means actuated by the engine for charging said reservoir, a feed pipe connected to said reservoir, a plurality of valves corresponding in number to the cylinders of the engine, and each connected with said feed pipe, inlet pipes connecting said valves individually with the respective cylinders of the engine, mechanism adapted to open said valves individually and in succession to correspond with the movements of 100 the pistons of the respective cylinders of the engine, a valve controlling said feed pipe, a check valve interposed between said charging means and reservoir, and a valved by-pass around said check valve for the purpose 105 110 115 120 specified.

3. A starting device for multi-cylinder internal combustion engines comprising a storage reservoir, an air compressor actuated by the engine for charging said reser- 125 130

voir, mechanism adapted to distribute air from said reservoir to the various cylinders of the engine for starting the same, and means for delivering air from said reservoir to said compressor whereby the latter may be operated as a motor for shifting the engine shaft off of dead center.

Signed at Chicago this 23rd day of January 1912.

JOHN F. KELLY.
